AMMUNITION MAKING MACHINERY

Antoine F. Gagne, Jr., Pompton Lakes, N. J., assignor to Remington Arms Company, Inc., Bridgeport, Conn., a corporation of Delaware

Application April 27, 1944, Serial No. 533,088

2 Claims. (Cl. 113—50)

1

The present invention relates to a die press, and particularly to ejector means for positively ejecting an article from a die of the press, and wherein the article engaged in the die is adapted to have its side wall laterally compacted within the die. An object of the invention is to provide ejector means, automatically actuated through the operation of the press, to the end that, irrespective of variation in the tightness with which the articles are engaged within the die after they are formed thereby, they are positively ejected in exact timed relation with the operating cycle of the press.

While the invention may find application in various types of presses, and in the formation of various articles, the present disclosure is illustrated by way of example in connection with a multiple station press of the type disclosed more fully in Patent No. 493,519, Richards, March 14, 1893. A press of this kind has an article transfer dial provided with article supporting apertures adapted to receive and transfer the articles from one operative station to another. During the forming operations upon the article, it may be moved out of an aperture of the dial by a suitable punch into a forming die which, in the particular machine shown in the drawings, is above the dial, and is thereafter moved back into an aperture of the dial for transfer to the next station. The invention is further illustrated by way of example in connection with the formation of bullets of armour piercing type, which comprise a bullet jacket having a steel core inserted therein, this core having a closure cap engaged over its heel end and retained in the jacket by crimping over and flattening the open end thereof. Following the crimping and flattening of the open end of the jacket, the bullet is subjected to a so-called heeling operation, for the purpose of tapering slightly the heel end of the bullet, this tapering operation consisting in laterally compressing the wall of the jacket adjacent its crimped end against the steel core, the jacket thus being tightly compacted between the tapered wall of the die and the steel core within the jacket.

The ejector means employed in connection with this operation usually consists of a spring loaded plunger, requiring an extremely heavy spring in order to effectually disengage and eject the bullet from the die. This has the disadvantage that the disengagement of a very tightly compacted bullet is uncertain, and is apt to be out of exact timed relation with the operating cycle of the machine. Also upon sudden dis-

2

engagement of the bullet from the die cavity the release of the extremely strong spring is apt to impart such impelling movement to the bullet that it will be carried through the transfer pocket of the dial and into the plunger passage below the dial, with the result that the transfer movement of the dial will be interfered with.

It is a further object of the present invention to provide positive ejector means adapted to disengage the bullet from the die through the operation of the reciprocating gate of the press, and in timed relation with the punch-carrying under carriage. Thus, disengagement takes place simultaneously with the lowering movement of the punch, and relatively light spring means may be employed for ejecting the bullet from the die to the dial, so that the impelling force thereon will be sufficient to engage it with the dial but will not be excessive.

20 With the above and other objects in view, an embodiment of the invention is shown in the accompanying drawings, and this embodiment will be hereinafter more fully described with reference thereto, and the invention will be 25 finally pointed out in the claims.

In the drawings—

Fig. 1 is a side elevation of the die carrying bracket and the ejector means associated therewith, and showing fragmentary portions of the 30 press for cooperation therewith, the reciprocating gate of the press being shown in its down position.

Fig. 2 is a front elevation thereof, partially in vertical section.

35 Fig. 3 is a sectional plan view, taken along the line 3—3 of Fig. 2.

Fig. 4 is a side elevation, partially in vertical section, showing the bullet engaged within the die and the reciprocating gate in its partially 40 raised position at the completion of the upstroke of the reciprocating under carriage, the dot-and-dash lines showing the successive positions of the gate as the under carriage moves to its down position, as the dial starts its transfer movement,

45 and as the gate reaches its up position where the dial is in the process of completing its movement, which can be about 60° after top dead center. The dial may, of course, complete the movement at top dead center.

50 Fig. 5 is a side elevation, partially in vertical section, showing the bullet on an enlarged scale in its state immediately preceding the heeling operation adapted to be performed by the die and ejector means of the invention.

55 Fig. 6 is a sectional view, also on an enlarged

scale, showing the bullet engaged with the heeling die.

Similar reference characters indicate corresponding parts throughout the several figures of the drawings.

Referring to the drawings, the press, illustrated by way of example, comprises a table 10 mounting an intermittently rotatable transfer dial 11 disposed at its marginal portion in spaced parallel relation above the table, a die block 12 being mounted in the space beneath the dial for cooperation therewith, as will presently more fully appear. The press includes a vertically reciprocating gate 13 disposed above the dial and a vertically reciprocating under carriage 14 disposed below the table, this under carriage adapted to have up and down movement in timed relation with the reciprocating gate during the raising movement of the gate. The dial is provided with a series of equally spaced circumferentially arranged article receiving pockets 15 having yieldable split sleeve article gripping members 16 therein, these gripping members being open at both ends and extending entirely through the dial. The dial is adapted to be moved intermittently to carry the articles inserted in its pockets from one to another of a series of stations during the latter part of the upstroke of the gate, and following the up and down movement of the under carriage, which occurs during the first part of the upstroke. The particular press illustrated is of the type where certain operations which require down pressure of a punch upon the article are performed in dies carried in the die block 12 below the dial, while other operations which require upward pressure of a punch upon the article are performed in dies mounted above the dial, the articles being moved from the dial into the respective dies, and then back into the dial during the stationary periods of the dial.

The bullet illustrated by way of example is one of the so-called armour piercing type, and comprises a bullet jacket 17 in which is engaged a steel core 18, the point of the core being pressed into a compacted point filling insert of lead 19 in the point of the jacket. The heel end of the steel core is tapered inwardly, as at 20, to provide a space for the insertion of the rim of a closure cap member 21, this closure cap member being retained by crimping over and flattening the open end of the jacket, as at 22.

The illustrated machine is adapted to assemble the closure cap 22 and to perform a series of finishing operations upon the bullet, the open ended jacket with the assembled steel core therein being inserted in the pockets of the dial at one point and then fed into successive relation with the several operative stations. The first operative station is the cap feeding station where a cap 21 is inserted into the open end of each jacket. At the next station the cap is seated, being forceably pressed downwardly into the jacket into covering engagement with the end of the steel core with its rim engaging in the space provided by the tapered end 20 of the core. This cap seating operation is performed in a die at the under side of the dial. At the next station the end of the jacket is crimped inwardly, this operation being performed in a die at the upper side of the dial. At the next station the crimped end of the jacket is flattened, so that the bullet is in the state as shown in Fig. 5.

The crimp flattening operation is performed in a die 23 provided in the die block 12 at the under side of the dial in vertical line with the dial pocket

15 and by a punch 24 carried by the gate 13 in vertical line with the die 23. In the base of the die 23 there is provided an ejecting punch 25 carried by the under carriage 14. During the 5 down stroke of the gate the punch 24 enters the pocket 15 of the dial and pushes the bullet therein downwardly through the pocket into the die 23 where it flattens the crimped end of the bullet jacket. During the raising movement of the gate 10 the under carriage 14 moves upwardly, causing the punch 25 to carry the bullet out of the die 23 back into the dial pocket 15, the under carriage thereupon moving downwardly to disengage the punch 25 from the dial, this up and down movement of the under carriage occurring during the first part of the upstroke of the gate. During the latter part of the upstroke of the gate, and after disengagement of the ejector punch 25 and the flattening punch 24 from the dial, the dial is 20 moved to transfer the bullet carried therein from the crimp flattening station to the next station. At this next station the heel tapering operation is performed upon the bullet, this being the operation with which the die and ejector means of 25 the present invention are particularly concerned.

Upon the table 10 there is mounted a bracket 26 having an angularly extending arm projecting over the dial and provided with a tubular cylindrical die holding head 27 in vertical alignment 30 with the heeling station of the dial next following the crimp flattening station in line with the punch 24 and die 23. Within the tubular head 27 there is engaged a sleeve member 28, having an annular flange 29 at its lower end engaging 35 the lower end of the head. In its upper portion the sleeve member is provided with a cylindrical piston chamber 30, and in its lower portion is provided with a cylindrical die receiving pocket 31, the chamber 30 and the pocket 31 being connected 40 by a reduced diameter passage 32. The upper end of the sleeve is interiorly threaded and is engaged by the threaded plug end 33 of a plug cap 34, bearing upon the upper end of the tubular head 27, tightening of the plug cap drawing the flange 30 upwardly against the lower end of the head 27 and thus securing the sleeve in place. The sleeve is held against rotation by a set screw 35 screwed into the lower end of the head 27 and having its head engaged in a pocket 36 provided 50 in the periphery of the flange 29. The plug cap is secured against rotation by means of a set screw 37 bearing upon the upper end of the head 27.

Within the chamber 30 there is provided a piston 38 having a lower stem portion 39 engaged in the passage 32, a vertical stem rod 40 being secured to its upper side and slidably engaged at its upper end portion within a central passage 41 in the plug cap. An ejector pin 42 is engaged in a 60 pocket 43 in the lower stem portion of the piston and is secured therein by means of a set screw 44 engaged in a recess 45 cut in the side of the pin. Within the piston chamber there is provided a helical compression spring 46 disposed between 65 the plug cap and the piston and exerting downward pressure upon the piston. A die block 47 is engaged in the die pocket 31 and is secured in seating relation therein by a retaining cap 48 screwed upon the lower threaded end of the sleeve 70 28, this die block being provided with a die cavity 49 for receiving the bullet to be formed, and provided in axial line above this pocket with a cylindrical passage 50 engaged by the ejector pin 42, the lower end of this pin being projected into the 75 die cavity in line with the lower end of the die in

the normal depressed position of the piston, and being raised to the upper end of the die cavity through the upward pressure of the bullet inserted therein, as will presently more fully appear.

The bullet is adapted to be inserted within the cavity by means of a punch 51 carried by the under carriage 14 and provided in its upper end with a pocket 52 for engaging the point end of the bullet. This punch moves upwardly during the initial upward movement of the gate 13, pushing the bullet from the retaining sleeve 16 of the pocket 15 of the dial upwardly into the cavity 49 of the die 41, the tapered form of the die cavity imparting a slightly tapered form to the heel of the bullet. Thereupon, and still during the upward movement of the gate 13, the punch 51 moves downwardly out of engagement with the dial, and it is during this movement that the ejector means of the present invention is adapted to be actuated.

The plug 34 is provided with a pair of spaced bearing ears 53, the bottom 54 of the space between these ears being inclined downwardly and rearwardly and having the upper end of the passage 41 located therein. A lever arm 55 is pivotally mounted at one end between the arms 53 upon a pin 56, rotatably supported at its ends in bearing bushings 57 in the arms and secured to the lever arm by means of a set screw 58 in the end of the arm engaged in a groove 59 in the pin. Upon the end of the arm there is provided a projecting lug 60 carrying a pressure screw 61 arranged to engage the upper end of the rod 40, when the latter is projected above the inclined surface 54 in the raised position of the piston, as shown in Fig. 4, and to depress the plunger rod through swinging movement of the arm imparted thereto through a lazy-tong connection with the gate 13. For this purpose the outer end of the lever arm 55 is connected by a pair of link members 62—62 to a fixture 63 secured by screws 64 to the under side of the gate, the link member being pivotally connected to the lever arm and to the fixture by cross pins 65 and 66, preferably fixed to one of the links and inserted through the lever arm and fixture and through the other link, which is retained thereon by means of washers 67 and cotter pins 68. Spacer washers 69 are preferably provided upon the pin 65 between the lever arm and the links.

In operation, the bullet is brought by the dial to the heeling station, the transfer movement of the dial taking place during the latter part of the raising movement of the gate 13, as indicated in Fig. 4. Thereupon the gate moves downwardly to its maximum down position and during this down movement the punches carried by the gate are brought into relation with the dies below the dial. As shown in Fig. 2, the punch 24 moves downwardly through the dial at the station preceding the heeling station, moving the bullet into the die 23 and flattening the crimped end. During the first part of the upward movement of the gate the under carriage moves upwardly and downwardly, its upward movement moving the ejecting punch 25 upwardly through the die 23 returning the bullet to the dial. At the same time the heeling station punch 51, also carried by the under carriage, moves upwardly and downwardly, its upward movement forcing the bullet at the heeling station into the die cavity 49 of the die 41, the engagement of the bullet in the cavity forcing the ejector pin 42, the piston 38 and the stem rod 40 upwardly, so that the upper end of the stem rod is projected above the inclined bot-

tom surface 54 of the plug cap. As the under carriage completes its upward movement the lever arm 55, which swings in clockwise direction during the upward movement of the gate, is brought into contact with the projected upper end of the stem rod, so that as the under carriage moves downwardly withdrawing the punch 51 from the die cavity the ejector pin is pressed downwardly by the combined action of the lever 55 and the spring 46, thus positively exerting disengaging force upon the upper end of the bullet within the die cavity. Irrespective of the tightness of the bullet in the cavity its disengagement and ejection takes place simultaneously with the withdrawing action of the punch 51, the action of the spring 46 projecting the ejector pin to the point where the bullet is forced back into the dial pocket. As soon as the bullet is fully engaged in the dial pocket, and the punch 51 descends below the dial, the dial is rotated to transfer the bullet to the next station, the completed bullet being finally ejected by a suitable ejector punch.

The form of the invention illustrated in the drawing and described herein is typical and illustrative only, and it is evident that the invention is capable of embodiments in other forms, all falling within the scope of the appended claims, which are to be broadly construed.

What is claimed is:

1. In a die press, the combination with a table; article supporting means movably mounted on said table; a gate reciprocably mounted above said supporting means; an under-carriage reciprocably mounted beneath said supporting means; a die having a die cavity fixedly mounted on said table above said supporting means; an article ejector mounted in said die and movable into and out of said die cavity; resilient means arranged normally to project said ejector into said die cavity, said ejector being adapted to be engaged and displaced therefrom by an article thrust into said die cavity from said supporting means; and means carried by said under-carriage constructed and arranged to engage an article in said supporting means to move said article therefrom up into said die cavity and to subsequently retire downwardly therefrom; of means to positively return the displaced ejector into said die cavity and thereby to eject the article therefrom comprising a stem on said ejector arranged to be moved from a normal position corresponding to the normal position of said ejector to a displaced position by displacement of said ejector from said die cavity, a lever arm pivotally supported on said table, one end of said lever arm being arranged to engage said stem in its displaced position and to positively move said stem to its normal position in response to predetermined movement of said lever arm; and means associated with said gate constructed and arranged to impart said predetermined movement to said lever substantially simultaneously with the retirement of said article moving means carried by the under-carriage.
2. In a die press, the combination with a table; article supporting means movably mounted on said table; a gate reciprocably mounted above said supporting means; an under-carriage reciprocably mounted beneath said supporting means; a bracket fixed to said table having a cylinder; a die having a die cavity fixedly mounted in the lower end of said cylinder above said supporting means; an article ejector slidably mounted in said cylinder having an ejector pin movable into and out of said die cavity; resilient means in said cylinder arranged normally to project said ejector

pin into said cavity, said pin being adapted to be engaged and displaced therefrom by an article thrust into said die cavity from said supporting means; and means carried by said under-carriage to engage an article in said supporting means to move said article therefrom up into said die cavity; of means to positively return the displaced ejector pin into said die cavity and thereby to eject the article therefrom comprising a stem on said ejector arranged to project upwardly in said cylinder and movable from a normal position therein corresponding to the normal position of said ejector pin to a displaced position by displacement of said ejector pin from said die cavity wherein the upper end of said stem projects above 15 the upper end of said cylinder, a toggle joint connected between said reciprocable gate and said fixed bracket, and a lug portion on one of the levers of the toggle joint arranged to engage the top of said stem in its displaced position to 20 positively move said stem to its normal position in

said cylinder in response to movement of said gate.
